FLUID OPERATING AND BRAKING SYSTEM
FOR CIRCUIT INTERRUPTERS

Ira W. Paterson, Milton, and John F. Chipman,
South Weymouth, Mass., assignors to Allis-
Chalmers Manufacturing Company, Milwaukee,
Wis., a corporation of Delaware

Application January 28, 1949, Serial No. 73,376

14 Claims. (Cl. 200—81.4)

1

This invention relates to electric switching devices of the type in which gas under pressure is utilized to operate a contact actuating means as well as a brake and more particularly to means for controlling the dissipation of the kinetic energy of the actuating means and parts associated therewith.

In fluid operated electric switches where the movable switch contact and its associated actuating means have an appreciable amount of mass inertia, the kinetic energy of the switch and actuating means must be dissipated when the switch contact reaches one or the other end position thereof. In prior art braking systems such energy has been absorbed by suitable springs or by frictional brakes. Such frictional braking systems have applied a braking effort that is independent of the operating effort applied to the switch actuating means to operate the same, or the braking effort is not correlated with and proportional to the operating effort applied to the switch under variable operating conditions.

It is therefore one of the objects of the present invention to provide a new and improved control system for circuit breakers of the fluid blast type.

Another object of the present invention is to provide a new and improved fluid operated actuating and control system for switching devices in which the braking effort of a fluid operated brake mechanism is in a substantially constant ratio to the operating effort applied to the switch actuating means at any operation thereof.

A further object of the invention is to provide a new and improved fluid operated brake which rapidly supplies a predetermined braking effort for arresting the operating movement of a fluid motor supplied at constant pressure and parts associated with and operated by it, and rapidly releases the fluid under pressure from the brake mechanism upon arresting the movement of the fluid motor and associated structure.

Objects and advantages other than those above set forth will be apparent from the following description when read in connection with the accompanying drawing in which:

Fig. 1 is a diagrammatic showing of a circuit breaker and control system therefor embodying the present invention; and

Fig. 2 is a view in cross section through a modification of the brake control valves and

2

the exhaust valves of the embodiment illustrated in Fig. 1.

The present invention is shown as applied to a fluid operated polyphase circuit breaker of the gas blast type, of which only the elements of one phase are shown. As shown in the drawing, one phase of the circuit breaker consists essentially of a fixed arcing contact 1 and a movable contact 2 connected in series with disconnect contacts 3 and 4 in an electric circuit through terminals 5. The arcing contacts 1 and 2 are housed in a tubular insulator 6 of ceramic material of which porcelain is an example. A base member 7 supports tubular insulator 6 in any suitable manner.

A conductive annular member 8 made in two parts is mounted on and supported by insulator 6. An insulating tube 11 mounted within and axially aligned with insulator 6 is rigidly supported by base member 7. Tube 11 surrounds the cooperating arcing contacts 1 and 2 and cooperates with conductive annular member 8 to define an arcing chamber 12.

Contact 1 is secured to a tubular portion of base member 7 extending into insulating tube 11. The cooperating movable contact 2 comprises an annular shaped arcing portion defining an orifice 14 and adapted to partially surround the top portion of stationary contact 1 upon engagement therewith. Movable contact 2 further comprises a sleeve portion 15 and forms therewith a piston of a fluid motor. Sleeve 15 is adapted to slide within guiding surfaces which in turn, constitute downward extending portions 16 and 17 of the conductive annular or cylindrical member 8. The upward stroke of sleeve 15 is limited by abutment of an annular projection thereof against a flange 18 backed by suitable shock absorbing material. The interior of sleeve 15 is insulated by a suitable material.

Arching chamber 12 contains an auxiliary probe electrode 19. This electrode, which is secured to a cover 22 and in electrical contact with member 8, is usually axially aligned with sleeve 15.

A plurality of rigid interconnecting conductors 23 disclosed and claimed in U. S. Patent 2,533,545, of Chester D. Ainsworth and Gustav 50 E. Jansson issued December 12, 1950 and assigned to the assignee of this application, electrically connect movable contact 2 to member 8 and in turn terminal element 5 which is secured to member 8.

Each rigid interconnecting conductor 23 is in

the form of a rocking contact lever which is in permanent contact with the conductive annular member 8 and sleeve 15 at all times. A plurality of spring means 24 provide a contact pressure between interconnecting conductors 23 and member 8 and sleeve 15, thus providing an electrical circuit connection therebetween. These springs have a dual function and additionally effect resetting or reclosing of contact 2 upon decrease of fluid pressure at movable contact 2.

Base member 7 is connected to a reservoir 27, constituting a source of arc extinguishing fluid under pressure. The fluid is supplied to the inlet portion of the arcing chamber 12 upstream of movable contact 2 for the purpose of directing a blast of arc extinguishing fluid under pressure between the arcing contacts and through the arcing chamber. The arc extinguishing fluid under pressure may be a suitable inert gas, but it will be assumed herein that the fluid is air under pressure of the order of 100 or more pounds per square inch.

The compressed air for operating the system is derived from a storage tank or compression system (not shown) and flows through a reducing valve 25 and a pipe line 26 to a blast manifold or reservoir 27. The air under pressure in reservoir 27 is intended to produce the arc extinguishing blast across the gaps formed between the pair of cooperating arcing contacts upon separation thereof. The arc extinguishing blast from reservoir 27 to the arcing contacts 1 and 2 is controlled by a blast valve 28 through a pipe line 29 interconnecting the blast valve 28 and the base member 7 which in turn communicates with the arcing chamber 12.

Blast valve 28 comprises fluid motors 31 and 32 for controlling a blast inlet port 44. Motor 31 comprises a cylinder 33, a piston 34, a piston return spring 35, a piston rod 36, and an inlet port 37. Motor 32 comprises a cylinder 41, a piston 42, a return spring 43 for piston 42, an exhaust port 45, and a valve 46 for closing exhaust port 45 under the action of a spring 47. Piston rod 36, when actuated by piston 34, opens valve 46 against the action of spring 47. As long as port 45 remains closed, air under pressure supplied from reservoir 27 to the space below piston 42 through a hole drilled in the piston cooperates with spring 43 to maintain the piston in the position shown.

A fluid pressure tank or reservoir 48 connected to the source of supply through reducing valve 25 is provided for supplying fluid under pressure to a fluid operated motor means 51 and a fluid operated brake mechanism 52. The motor and the brake control the movable disconnect contact of the circuit breaker. In order to prevent a backflow of compressed air from reservoir 48 into pipe line 26 upon decrease of pressure in pipe line 26 due to the reduction of pressure in reservoir 27 after the occurrence of an arc extinguishing blast of air through blast valve 28, a check valve 53 is provided between pipe line 26 and reservoir 48. Check valve 53 is of the commercial type having a small bleed hole permitting tank 48 to bleed gradually into pipe system 26 if the pressure remains lower in system 26 than in tank 48 for a considerable period of time. The purpose of this bleed hole is to cause pressure lockout means to make any operation by air derived from tank 48 impossible in case the pressure in manifold 27 drops permanently below the safe limit required for interruption of the circuit by air blast.

Fluid motor 51 comprises a cylinder 54 and a piston 56. Piston 56 is mounted on a piston rod 57 which is axially aligned with cylinder 54 and extends through the cylinder covers. A slide valve port 59 in piston rod 57 of motor 51 acts to vent closing air in breaker closed position to aid fast reversal of piston 56. Cylinder 54 provides ports 58 and 62 for intake and exhaust purposes. Port 61 is provided for blast valve reset control.

Brake 52 comprises brake shoes 63 provided with a brake lining 64 acting on a drum 65 connected to a shaft 66 which actuates disconnect contact 3. When air under pressure is fed to brake cylinder 67, a piston 68 actuates brake shoes 63 and they tighten about the drum 65, thus arresting movement of shaft 66.

Slide or control means such as valves 71 and 72 are provided for admitting compressed air from reservoir 48 to fluid brake 52 and comprise cylinder 73 and 74, pistons 75 and 76, piston rods 77 and 78, and inlet and outlet ports 81, 82, and 83, 84, respectively. Slide valves 71 and 72 are operated by means of a crank mechanism secured to piston rods 77 and 78 which comprises a pair of slotted arms or links 85 and 86, each having a lost motion connection with the operating shaft 66 of the disconnect switch contact 3. Shaft 66 is operated by the disconnect contact operating fluid motor 51.

A second pair of slide valves 87 and 88 which, for example, may comprise a common body member 91 and a pair of pistons 92 and 93 are connected to slide valves 71 and 72, respectively, to serve the purpose of dumping or exhausting compressed air from the brake mechanism 52 upon dissipation of the kinetic energy of the disconnecting switch mechanism. Piston 92 is relatively small in diameter as compared to piston 93. This is intended to provide a trip predominating feature in case contradictory operating impulses are being supplied to slide valves 71 and 72. Cylinder body member 91 provides an inlet port 95 for piston 93 and an inlet port 96 for piston 92. Pistons 92 and 93 are provided with a common spring 94 which positions them in the position shown in the absence of air pressure in ports 95 and 96. Exhaust ports 97 and 98 provided in member 91 for pistons 93 and 92, respectively, are connected to a pair of exhaust ports 101 and 102 of slide valves 72 and 71, respectively.

A pair of piston valves 103 and 104 provide interlocking means for effecting proper sequential operation of the opening of the blast valve 28, the initiation of the opening operation of the disconnecting switch contact 3, and the reclosing of the blast valve 28. Piston valves 103 and 104 comprise cylinders 105 and 106, pistons 107 and 108, and return springs 111 and 112, respectively.

A pair of opening and closing valve means 114 and 115 control the actuating means for the circuit breaker. Valve means 114, 115 may be of any suitable known type and are diagrammatically shown as valves of the magnetic type comprising casings 116 and 117, valve elements 118, 121, armatures 122, 123 and coils 124 and 125, respectively.

The circuit breaker illustrated in the drawing is shown with the disconnect contacts in the open circuit position and the pneumatic control system in the corresponding position. A closing operation is initiated by energization of the closing solenoid valve 115, thereby permitting air un-

der pressure from reservoir 48 to pass through a pipe line 126 to and through valve 115, through a pipe line 127 and inlet port 62 to fluid motor 51. Part of the air flow through pipe line 127 passes through the pipe line 128 to the inlet port 81 of slide valve 71. As long as piston 75 of slide valve 71 is in the position illustrated in the drawing inlet port 81 is closed. Operation of solenoid valve 115 results in moving piston 56 of motor 51 from right to left to actuate shaft 66 and thereby close the disconnect contacts. After a predetermined travel of piston 56, shaft 66 actuates slotted arm 85, piston rod 77 and piston 75. The latter then opens inlet port 81 of slide valve 71. Air under pressure then flows from pipe line 128 through slide valve 71, outlet port 82, through a pipe line 129 to the fluid brake 52. The brake decelerates shaft 66 by absorbing the kinetic energy of the shaft and of contact 3. Simultaneously with rotation of shaft 66, piston 76 of valve 72 is caused to move to the left by the action of the reset spring behind it, thereby closing ports 84 and 83 and preventing exhausting of live air through lines 109, 157 and 156.

A port 102 in cylinder 73 of slide valve 71 is connected to slide valve 87 and more particularly port 98 thereof through pipe line 134. The pressure impulse initiated through opening of solenoid valve 115, however, is also transmitted to port 96 and results in moving slide dumping valve 87 and more particularly piston or valve 92 thereof to the closed position or that position where port 98 is closed. Exhaust of air from pipe lines 128, 129 to atmosphere through ports 98, 135 is thereby prevented.

Upon return of solenoid valve 115 to the position shown, pressure in pipe line 128 decays by leakage of air past the movable elements connected in line 128 and by venting to atmosphere through port 130 of valve 115. Slide valve port 59 acts to vent closing air when the breaker reaches closing position, thereby rapidly dropping the pressure in pipe lines 127, 128. When the pressure has decayed in pipe lines 127 and 128 to a predetermined value, dumping or slide valve 87 is reset by the action of spring 94, resulting in immediate dumping or exhausting of fluid under pressure from fluid brake 52 through exhaust port 135 of valve 87.

When the solenoid trip valve 114 is energized, compressed air flows from reservoir 48 through trip valve 114, a pipe line 135, and inlet port 137 into piston valve 103. An outlet port 138 of piston valve 103 transmits the pressure impulse through a pipe line 141 to the inlet port 37 of blast valve 28 and of the blast valves of the other phases of the circuit breaker. The piston 34 of motor 31 moves under the action of the pressure impulse to open exhaust port 45, thus reducing the pressure in the space below piston 42. This permits air from reservoir 27, communicating with air blast valve 28 through a pipe line 142 and in inlet port 143, to move piston 42 of fluid motor 32 against the action of spring 43. The movement of piston 42 under the air pressure from reservoir 27 opens the inlet port 44 and permits an air blast to move through a pipe line 29 to arcing contacts 1 and 2 of the circuit breaker. The air blast causes separation of the arcing contacts 1 and 2 and extinguishment of the arc occurring therewith.

An outlet port 145 in blast valve 28 communicating with pipe line 29 permits a blast of air to travel through a pipe line 146 to an inlet port 147 of piston valve 103 upon the transit of a pressure wave through pipe line 29. The pres-

sure impulse transmitted through pipe line 146 moves piston 107, which opens an outlet port 148 and closes outlet port 138 of piston valve 103. The pressure impulse transmitted through pipe line 136, then passes through outlet port 148, pipe line 151, and inlet port 58 of fluid motor 51. This pressure impulse moves piston 56 of motor 51 from left to right, as indicated in the drawing, and the piston opens the disconnect contacts through shaft 66.

The travel of piston 56 of fluid motor 51 from left to right results, through the movement of piston rod 78 of slide valve 72, in the opening of inlet port 83 and outlet port 84. At the same time, link 85 allows resetting of piston 75 of seal ports 82 and 81 of valve 71 thereby preventing exhausting of live air being fed to line 129 through port 84 from inlet port 83 and line 156. A pressure impulse is thus permitted to flow from piston valve 103, through a pipe line 156, inlet port 83, outlet port 84, pipe line 129 to fluid brake 52. This results in operation of fluid brake 52 upon a predetermined travel of the movable disconnect contact 3. Any pressure impulse in pipe line 156 acts upon slide valve 88, through a pipe line 157 and port 95. Piston 93 of slide valve 88 is then moved against the action of spring 94 and closes normally open ports 97 and 161 of valve 88 which are provided for dumping or exhausting air from the fluid brake 52 through an exhaust port 101 of slide valve 72 and a pipe line 109.

Upon a predetermined travel of piston 56 of motor 51, an outlet port 61 is opened thereby and air under pressure is permitted to flow through a pipe line 152 to piston valve 104 through an inlet port 153. Piston 108 of valve 104 moves from right to left and vents pipe line 141 through inlet and exhaust ports 154 and 155 respectively, resulting in reclosing of the blast valve.

Upon reclosure of blast valve 28 and the resetting of piston valve 103 due to the reduction or decay of pressure in pipe line 146, port 148 of piston valve 103 is closed. Reduction of the pressure in pipe line 156 as a result of leakage of air past the movable elements such as pistons 107 and 56 connected therewith results in resetting of slide valve 88 under the action of spring means 94 and permits dumping of air under pressure from the fluid brake 52 through the exhaust port 101 in slide valve 72, pipe line 109 and exhaust port 161.

If closing and opening pressure impulses are substantially simultaneously initiated by solenoid valves 115 and 114, respectively, the trip predominating feature of slide valves 88 will permit only the completion of the opening cycle of the circuit breaker. Thus, when the closing impulse is initiated by valve 115, a pressure impulse is transmitted from reservoir 48 through valve 115, pipe line 127, pipe line 128 and inlet port 96 of slide valve 87. This pressure impulse moves piston 92, which closes port 98 of slide valve 87. The pressure in pipe line 127 moves piston 56 of motor 51 from right to left, and piston 56 in turn moves piston 75 of slide valve 71 from left to right and piston 76 of slide valve 72 from right to left. The movement of piston 75 from left to right opens inlet port 81 of slide valve 71 and permits air to flow through pipe line 129 to the fluid brake 52, and the movement of piston 76 from right to left closes ports 83 and 84.

If, however, a contradictory trip impulse was initiated by valve 114 shortly after or at the same time as the breaker closing impulse, air under

pressure flows through trip valve 114, pipe line 136, inlet port 137 of valve 103, outlet port 138 of valve 103, pipe line 141 and inlet port 31 of air blast valve 28. The air blast valve is actuated, permitting opening of the arcing contacts 1 and 2. Part of the air passing through blast valve 28 is transmitted through a pipe line 146 to valve 103 and moves piston 107 thereof from right to left. This movement of piston 107 opens outlet port 148 of valve 103 and permits air under pressure to flow through pipe line 156 to the inlet port 95 of slide valve 88. Because the diameter of piston 93 is greater than the diameter of piston 92, piston 93 moves from left to right and moves piston 92 of slide valve 87 against the pressure of pipe line 128, urging it from left to right. Upon movement from left to right of piston 92 of slide valve 87 ports 98 and 135 are opened, thus permitting exhausting brake 52. Ports 98, 135 also exhaust the air being admitted to the right side of piston 56 through valve 115, thereby permitting a complete opening cycle of the circuit breaker to occur. A slide valve port 59 in piston rod 57 of motor 51 also acts to vent closing air in breaker closed position to aid fast reversal of piston 56.

Fig. 2 illustrates a modified structure combining the brake control valves 71 and 72 with the pressure responsive exhaust valves 87 and 88 in a single self-sustained structural unit.

Although but two embodiments of the present invention have been illustrated and described, it will be apparent to those skilled in the art that various changes and modifications may be made therein without departing from the spirit of the invention or from the scope of the appended claims.

It is claimed and desired to secure by Letters Patent:

1. An electric circuit interrupter comprising a pair of relatively movable cooperating contacts, reciprocating motor means for relatively moving said contacts, a fluid operated brake mechanism of the frictional type for arresting relative movement of said contacts, a source of fluid under pressure, valve means distinct from said motor means for admitting fluid under pressure from said source to said brake mechanism, and a linkage operated by said motor means for operating said valve means upon a predetermined contact operating movement of said motor means.

2. An electric circuit interrupter comprising a pair of relatively movable cooperating contacts, a rocking shaft for relatively moving said contacts, reciprocating motor means for rocking said shaft, a fluid operated brake mechanism for arresting the rocking motion of said shaft, said brake mechanism including a brake drum fixedly mounted on said shaft and friction elements adapted to cooperate with said drum, a source of fluid under pressure, a brake valve distinct from said motor means for admitting fluid under pressure from said source to said brake mechanism, a mechanism including a lost motion connection operated by said shaft for actuating said brake valve upon a predetermined contact operating movement of said motor means, and valve means for relieving pressure in said brake mechanism after cessation of the rocking motion of said shaft.

3. An electric circuit interrupter comprising a pair of relatively movable cooperating contacts, fluid operated motor means for relatively moving said contacts, a fluid operated brake mechanism of the frictional type for arresting the relative

movement of said contacts, a main source of fluid under pressure, an auxiliary source of fluid under pressure, a pressure responsive valve permitting substantially unidirectional fluid flow from said main source to said auxiliary source and precluding substantial reverse flow of fluid under pressure, first valve means distinct from said motor means for admitting fluid under pressure from said auxiliary source to said brake mechanism, a second valve means for admitting fluid under pressure from said auxiliary source to said motor means, and a linkage operated by said motor means for operating said first valve means upon a predetermined contact operating movement of said motor means.

4. An electric circuit interrupter comprising a pair of relatively movable cooperating contacts, a fluid motor of the reciprocatory type for relatively moving said contacts, a fluid operated brake mechanism of the frictional type for arresting relative movement of said contacts, a source of fluid under pressure, a pair of brake valves for alternately admitting fluid under pressure from said source to said brake mechanism, and a rocking lever supported by a shaft and operated by said fluid motor for operating said pair of brake valves, said rocking lever having a pair of arms situated on different sides of said shaft and forming part of a linkage for opening either of said pair of brake valves and closing simultaneously the other of said pair of brake valves, said linkage including a pair of lost motion connections for opening either of said pair of brake valves upon a predetermined contact operating movement of said motor means.

5. An electric circuit interrupter comprising a pair of relatively movable cooperating contacts, a fluid motor of the reciprocatory type for relatively moving said contacts, a fluid operated brake mechanism of the frictional type for arresting relative movement of said contacts, a source of fluid under pressure, a pair of brake valves for alternately admitting fluid under pressure from said source to said brake mechanism, a rocking lever supported by a shaft and operated by said fluid motor for operating said pair of brake valves, said rocking lever having a pair of arms situated on different sides of said shaft and forming part of a linkage for opening either of said pair of brake valves and closing simultaneously the other of said pair of brake valves, said linkage including a pair of lost motion connections for opening either of said pair of brake valves upon a predetermined contact operating movement of said motor means, and a pair of valve means for relieving the pressure in said brake mechanism after cessation of the movement of said contacts, each of said pair of valve means being associated with one of said pair of brake valves and adapted to relieve the pressure in said brake mechanism through the brake valve with which it is associated.

6. In an electric switching device the combination of a fluid motor comprising a cylinder and a piston operatively arranged therein, a fluid operated brake mechanism for arresting the stroke of said piston at either end of said cylinder, a source of fluid under pressure, a pair of valve means for admitting fluid under pressure from said source selectively to either end of said cylinder, motor fluid supply conduits and brake fluid supply conduits for dividing the flow of fluid under pressure issuing from each of said pair of valve means into a motor supply flow and a separate brake supply flow, a pair of brake valves

one in each of said brake fluid supply conduits, and a crank mechanism operated by said fluid motor for operating said pair of brake valves, said crank mechanism comprising a pair of lost motion connections adapted to open either of said pair of brake valves upon a predetermined contact operating movement of said motor means.

7. In an electric switching device the combination of a fluid motor comprising a cylinder and a piston operatively arranged therein, a fluid operated brake mechanism for arresting the stroke of said piston at either end of said cylinder, a source of fluid under pressure, a pair of valve means for admitting fluid under pressure from said source selectively to either end of said cylinder, motor fluid supply conduits and brake fluid supply conduits for dividing the flow of fluid under pressure issuing from each of said pair of valve means into a motor supply flow and a separate brake supply flow, a pair of brake valves one in each of said brake supply conduits, a crank mechanism operated by said fluid motor for operating said pair of brake valves, said crank mechanism comprising a pair of lost motion connections adapted to open either of said pair of brake valves upon a predetermined contact operating movement of said motor means, and a pair of pressure responsive exhaust valves for relieving the pressure in said brake mechanism alternatingly through one of said brake valves after cessation of the relative movement of said piston and cylinder.

8. In an electric switching device the combination of a fluid motor comprising a cylinder and a piston operatively arranged therein, a fluid operated brake mechanism for arresting the stroke of said piston at either end of said cylinder, a source of fluid under pressure, a pair of valve means for admitting fluid under pressure from said source selectively to either end of said cylinder, motor fluid supply conduits and brake fluid supply conduits for dividing the flow of fluid under pressure issuing from each of said pair of valve means into a motor supply flow and a separate brake supply flow, a pair of brake valves one in each of said brake supply conduits, a crank mechanism operated by said fluid motor for operating said pair of brake valves, said crank mechanism comprising a pair of lost motion connections adapted to open either of said pair of brake valves upon a predetermined contact operating movement of said motor means, a pair of exhaust ports one in each of said brake valves, said exhaust ports being open and closed upon a predetermined movement of said crank mechanism, and a pair of pressure responsive exhaust valves for relieving the pressure in said brake mechanism through said exhaust ports in response to a predetermined pressure condition in said brake supply conduits.

9. In an electric switching device the combination of a fluid motor comprising a cylinder and a piston operatively arranged therein, a fluid operated brake mechanism for arresting the stroke of said piston at either end of said cylinder, a source of fluid under pressure, a pair of valve means for admitting fluid under pressure from said source selectively to either end of said cylinder, motor fluid supply conduits and brake fluid supply conduits for dividing the flow of fluid under pressure issuing from each of said pair of valve means into a motor supply flow and a separate brake supply flow, a pair of brake valves one in each of said brake supply conduits, a crank mechanism operated by said fluid motor for operating said pair of brake valves, said crank

mechanism comprising a pair of lost motion connections adapted to open either of said pair of brake valves upon a predetermined contact operating movement of said motor means, and a pair of pressure responsive exhaust valves for relieving the pressure in said brake mechanism alternatingly through one of said brake valves after cessation of the relative movement of said piston and cylinder, said pair of brake valves and said pair of pressure responsive exhaust valves being combined in a single self-sustained structural unit.

10. In an electric switching device the combination of a fluid motor comprising a cylinder and a piston operatively arranged therein, a fluid operated brake mechanism for arresting the stroke of said piston at either end of said cylinder, a source of fluid under pressure, a pair of valve means for admitting fluid under pressure to said source selectively to either end of said cylinder, motor fluid supply conduits and brake fluid supply conduits for dividing the flow of fluid under pressure issuing from each of said pair of valve means into a motor supply flow and a separate brake supply flow, a pair of brake valves one in each of said brake supply conduits, a crank mechanism operated by said fluid motor for operating said pair of brake valves, said crank mechanism comprising a pair of lost motion connections adapted to open either of said pair of brake valves upon a predetermined contact operating movement of said motor means, and a pair of pressure responsive exhaust valves for relieving the pressure in said brake mechanism alternatingly through one of said brake valves after cessation of the relative movement of said piston and cylinder, a pair of axially aligned relatively movable pistons arranged within said cylinder, a common resilient means mounted between and axially aligned with said pistons for biasing said pistons to valve open position, and means for actuating said pistons against the biasing action of said resilient means to valve closed position, one of said pistons having a larger diameter than the other so as to actuate the other of said pistons to valve open position when both pistons are actuated simultaneously by said actuating means.

11. An electric circuit interrupter comprising a pair of relatively movable cooperating arcing contacts, a pair of relatively movable cooperating disconnect contacts, means for relatively moving said arcing contacts, fluid operated motor means for relatively moving said disconnect contacts, a fluid operated brake mechanism of the frictional type for arresting the relative movement of said disconnect contacts, a main source of fluid under pressure, a first auxiliary source of fluid under pressure connected to said main source for providing a blast of fluid adjacent said arcing contacts upon separation thereof, a second auxiliary source of fluid under pressure connected to said main source independently of said first auxiliary source, a pressure responsive valve providing for unidirectional fluid flow from said main source to said second auxiliary source and precluding substantial reverse flow of fluid under pressure, and means for supplying fluid under pressure from said second auxiliary source at substantially the same pressure to both said motor means and said brake mechanism.

12. An electric circuit interrupter comprising a pair of relatively movable cooperating arcing contacts, a pair of relatively movable cooperating disconnect contacts, means for relatively

moving said arcing contacts, fluid operated motor means for relatively moving said disconnect contacts, a fluid operated brake mechanism of the frictional type for arresting the relative movement of said disconnect contacts, a main source of fluid under pressure, a first auxiliary source of fluid under pressure connected to said main source for providing a blast of fluid adjacent said arcing contacts upon separation thereof, a second auxiliary source of fluid under pressure connected to said main source independently of said first auxiliary source, a pressure responsive valve providing for unidirectional fluid flow from said main source to said second auxiliary source and precluding substantial reverse flow of fluid under pressure, means for supplying fluid under pressure from said second auxiliary source at substantially the same pressure to both said motor means and said brake mechanism, and valve means for relieving the pressure in said brake mechanism after arresting the movement of said disconnect contacts.

13. An electric circuit interrupter of the fluid blast type comprising a pair of cooperating arcing contacts, a second pair of relatively movable cooperating contacts in series with said first mentioned contacts, a main source of fluid under pressure, a first auxiliary source of fluid under pressure connected to said main source, means for establishing an arc extinguishing fluid blast from said first auxiliary source adjacent said arcing contacts, a second auxiliary source of fluid under pressure connected to said main source independently of said first auxiliary source, a valve interconnecting said auxiliary sources providing for substantially unidirectional flow of fluid from said first auxiliary source to said second auxiliary source and precluding substantial reverse flow of fluid upon decrease in pressure of said first auxiliary source, a fluid operated motor for relatively moving said second pair of contacts, a fluid operated brake mechanism of the frictional type for arresting the relative movement of said second pair of contacts, and means for supplying

fluid under pressure from said second auxiliary source at substantially the same pressure to both said fluid operated motor and said brake mechanism.

5 14. An electric circuit interrupter comprising a pair of relatively movable cooperating arcing contacts, a pair of relatively movable cooperating disconnect contacts, means for actuating said arcing contacts, fluid operated motor means for relatively moving said disconnect contacts, a fluid operated brake mechanism of the frictional type for arresting relative movement of said disconnect contacts, a main source of fluid under pressure, a first auxiliary source of fluid under pressure connected to said main source for providing a blast of fluid adjacent said arcing contacts upon separation thereof, a second auxiliary source of fluid under pressure, a distribution system for fluid under pressure supplied from said 10 main source through a reducing valve to said second auxiliary source, said distribution system providing for unidirectional flow from said distribution system to said second auxiliary source and precluding a substantial reverse flow of fluid under pressure, and means for supplying fluid under pressure from said second auxiliary source to both said motor means and said brake mechanism.
